(57) CLAIM

The ornamental design for an item of footwear, as shown and described.

DESCRIPTION

FIG. 1 shows a right (medial) side perspective view along the side and bottom of the item of footwear for a right foot showing the new design (an item of footwear for a left foot being a mirror image).

FIG. 2 shows a front elevational thereof.

FIG. 3 shows a rear elevational view thereof.

FIG. 4 shows a left (lateral) side elevational view thereof.

FIG. 5 shows a right (medial) side elevational view thereof.

FIG. 6 shows a top plan view thereof; and,

FIG. 7 shows a bottom plan view thereof.

Features illustrated with the broken lines form no part of the claimed design and are merely to illustrate an exemplary environment for the portion illustrated with solid lines.

1 Claim, 6 Drawing Sheets
